UNITED STATES PATENT OFFICE

ARNOLD R. KRAUSE AND HOWARD O. HUTCHENS, OF EAU CLAIRE, WISCONSIN,
ASSIGNORS TO GILLETTE RUBBER COMPANY, OF EAU CLAIRE, WISCONSIN, A COR-
PORATION OF WISCONSIN

TUBE DRILL

Application filed July 5, 1927. Serial No. 203,815.

This invention relates to a tube drill or rotary punch for perforating the valve stem hole in automobile inner tubes.

It is an object of this invention to provide 5 an improved machine of the class described wherein positive means are provided for ejecting the cut out rubber discs from the interior of the punch. In leather and paper punches, the discs are allowed to accumulate 10 in the hollow joint of the punch until a sufficient number are present to force the uppermost discs out through a side opening in the punch. With rubber punches, however, the side outlet in a rotary punch is undesirable 15 as well as causing trouble due to the sticky and elastic character of the discs which are compressed at each stroke of the punch, and are as apt to stick in the punch and expand downwardly upon the return stroke as they 20 are to move upwardly and out through the side outlet. In practice, the use of such a punch requires frequent stoppages to clear the punch and it is accordingly an object of 25 this invention to provide a mechanical ejector for the cut discs which operates on the return stroke of the punch.

It is also an object of this invention to provide means for feeding a cutting or lubricating liquid to the point of the punch to assist 30 in the cutting operation and prevent sticking of the tacky cut surfaces.

Other and further important objects of this invention will be apparent from the disclosures in the specification and the accompanying drawings.

This invention (in a preferred form) is illustrated in the drawings and hereinafter more fully described.

On the drawings:

40 Figure 1 is a side elevation of a machine embodying the features of this invention.

Figure 2 is a front elevation thereof.

Figure 3 is a top plan view of the machine.

Figure 4 is an enlarged section on the line 45 IV-IV of Figure 3.

Figure 5 is a fragmentary detail section of the lubricant feeding means for the punch.

As shown on the drawings:

50 The apparatus comprises a pedestal 10 supporting a column 11 near the top of which

are secured collars 12 and 13, collar 12 supporting an outstanding arm 14, the outer end of which carries an inserted crowned head plug 15, preferably hardened, which serves as an anvil for the punch or drill to be described hereinafter. 55

The collar 13 forms part of a double armed bracket, the rear arm 16 of which forms a shelf for a motor 17 which drives the rotary cutter pulley 18 by means of a round belt 19. The drive is shown as a right angle drive in order to provide for belt alignment during the vertical movement of the cutter pulley 18. 60

The front arm 20 extends above and parallel to the anvil arm 14 and is forked at 21 on the outer end in alignment with the anvil plug to receive a reciprocable sleeve 22 carrying a hollow punch spindle 23 journaled therein in ball bearings 24. The sleeve 22 is reciprocated by means of a fork ended lever 25, the forks 26 of which engage pins 27 carried by the sleeve. This lever 25 is pivoted at 28 to the arm 20 and the other end is engaged by a link 29 connected to a foot lever 30, a spring 31 acting to pull the link downwardly to 70 normally hold the sleeve 22 in its upper position. 75

The punch proper is indicated at 32 in Figure 4, and is screwed into the end of the punch spindle in order that it may be replaced or sharpened readily by removal from the spindle, wrench flats being provided on both the punch and the spindle. Stripping fingers 33 are shown in the figures to prevent the punched tube from moving up on the shank of the punch. 80

A belt guard 34 is mounted on the arm 20 to cover the pulley 18, the mounting for this guard also securing a bracket 35 in place above the hollow punch spindle. A rod 36 is secured in this bracket and extends down through the spindle 22 and punch 32, the lower end of the rod terminating just within the edge of the punch so that on the return stroke of the punch, the cut plug carried therein is ejected by the stationary rod 36. An inclined funnel 37 is mounted in the bracket 35 with the tip 38 of the funnel closely adjacent the rod 36 to deliver fluid thereto. A container 39 for cutting and lubricating 100

liquid is supported by the column 11 and feeds into the funnel 37 through a valve 39.

The operation of the machine will be easily understood from the foregoing. The operator slips one end of an unspliced tube over 5 the anvil arm 14 and depresses the foot lever, forcing the rotating punch into the tube. On the return stroke of the punch the rod 36 pushes the cut plug out of the punch.

10 We are aware that many changes may be made, and numerous details of construction may be varied through a wide range without departing from the principles of this invention, and we therefore do not purpose limiting 15 the patent granted hereon, otherwise than necessitated by the prior art.

We claim as our invention:

1. In combination, in a device for forming valve stem holes in inner tubes, a support including 20 an elongated arm arranged to receive an inner tube thereover, a crowned element connected to an end of said arm formed to serve as an anvil, a rotary cutting tool above the anvil, and means for depressing the tool so as to bring it into contact with the portion 25 of the tube disposed on said anvil to cut a valve stem hole in said portion.

2. In combination, in a device for forming valve stem holes in inner tubes, a support including 30 an elongated arm arranged to receive an inner tube thereover, a crowned element connected to an end of said arm formed to serve as an anvil, a rotary cutting tool above the anvil, means for depressing the tool so as 35 to bring it into contact with the portion of the tube disposed on said anvil, and an independent rod extending into said tool and arranged to force and remove rubber blanks from the tool on the return movement of the tool.

40 In testimony whereof, we have hereunto subscribed our names.

ARNOLD R. KRAUSE.
HOWARD O. HUTCHENS.
